LIFE BELT

Roger A. Nolan, United States Navy

Application April 20, 1934, Serial No. 721,503

2 Claims. (Cl. 9—17)

(Granted under the act of March 3, 1883, as
amended April 30, 1928; 370 O. G. 757)

This invention relates to a life belt, and has for an object to provide an improved life belt capable of supporting the human figure in the water with the body in a forwardly inclining position but with the nose kept safely out of water so that the wearer will not be in danger of drowning (even though he become unconscious) yet will be capable of propelling himself through the water without undue exertion.

10 Another object of this invention is to provide a life belt made in the form of an elongated rectangular buoyant strap that may be connected and easily adjusted on the body of the wearer without assistance.

15 A further object of this invention is to provide a long rectangular life belt and an improved method of placing the belt on the human figure so that it will at all times support the body in a position for easy breathing and easy swimming.

20 A still further object is to provide a long rectangular life belt having means for adjusting its length so that it may fit human figures of different sizes.

Another object is to provide a life belt which, 25 when not in use, may be connected to similar life belts and stored in a roll available for quick separation and distribution when needed.

In the drawing:

Fig. 1 is a front plan view of a human figure 30 wearing this improved life belt;

Fig. 2 is a rear view of Fig. 1;

Fig. 3 is a plan view of the front of one end of the life belt;

Fig. 4 is a similar view of the other end of the 35 life belt;

Fig. 5 is a rear view of Fig. 3;

Fig. 6 is a rear view of Fig. 4; and

Fig. 7 is a top edge view of Fig. 5.

The belt shown at 10 is rectangular in outline 40 and consists of a plurality of panels 11 separated by stitching 12, each panel being stuffed with a suitable flotation material such as kapok. One end panel 13 is left unfilled so as to provide means for adjusting the length of the belt. Fastening

45 means such as strap ends 15 are secured to end panel 13 and similar strap means 16 are secured to the adjoining kapok-filled panel. The opposite end panel 11 of the belt is provided with a co-operating buckle means 17 adapted to receive

50 either the strap ends 15 or 16. When used by a large wearer the strap ends 15 will cooperate with buckles 17 but when used by a wearer of smaller proportions the end panel 13 is folded over the adjoining panel 11 at the same time

55 folding the strap ends 15 therein, the panel 13

being held in folded-over position by snap fasteners 18 suitably placed on the end of panel 13 and on the belt 10 as at 19. The belt is approximately seven inches wide and six feet, ten inches in length, although of course these dimensions may be varied within suitable limits.

When not in use, the belt may be stored by securing it to a series of adjoining belts and forming them in a roll in the same manner that wrapping paper is formed in a roll. When necessary to use the belts, they are disconnected one from the other and distributed. The wearer places the middle of the belt over the chin and neck, crosses it, brings it over the shoulders, crosses it over the back and then under the arms 15 and fastens it across the chest, as shown in Figs. 1 and 2, using either the strap ends 15 or strap ends 16, depending on the size of the wearer. As will be observed, the belt is then approximately in the form of a figure eight, having the upper 20 smaller loop extending around the neck and the lower larger loop extending around the chest. When worn in this manner the wearer has his arms free from restriction and capable of easy use either for swimming or for rowing a boat, 25 and when in the water, the portion of the belt over his chin holds the nose above water even though he may become unconscious.

The invention described herein may be manufactured and used by or for the Government of 30 the United States of America for governmental purposes without the payment of any royalties thereon or therefor.

I claim:

1. A substantially flattened rectangular life 35 belt, flotation material secured within said life belt, said life belt being divided into a plurality of rectangular panels preventing the flotation material therein from being displaced, one end panel of said belt being free of flotation material, fastening means secured to said end panel free of flotation material, additional fastening means secured to the adjoining panel and cooperating fastening means secured to the other end of said belt and adapted to cooperate with either 40 fastening means, said belt being of sufficient length to form a figure eight about the wearer, the smaller upper loop encircling the throat and the larger lower loop encircling the body, said panels being sufficiently wide and flat so that the 45 throat encircling loop may extend from the chest to over the mouth to protect the mouth against spray.

2. A substantially flattened rectangular life 50 belt, flotation material secured within said life belt,

55 folding the strap ends 15 therein, the panel 13

belt, said life belt being divided into a plurality of rectangular panels preventing the flotation material therein from being displaced, one end panel of said belt being free of flotation material, fastening means secured to said end panel free of flotation material, additional fastening means secured to the adjoining panel and cooperating fastening means secured to the other end of said belt and adapted to cooperate with either fasten-

ing means, said belt being of sufficient length to form a figure eight about the wearer, the smaller upper loop encircling the throat and the larger lower loop encircling the body, and cooperating fastening means on said end panel free of flotation material and on said belt for holding said end panel in folded position with the fastening means on said adjoining panel available for use.

ROGER A. NOLAN.
